THROTTLE DASHPOT

Gordon W. Harry, Flushing, Mich., assignor to
 General Motors Corporation, Detroit, Mich., a
 corporation of Delaware

Application May 10, 1951, Serial No. 225,497

15 Claims. (Cl. 267—1)

1

This invention relates to pneumatic devices for resisting or retarding the movement of other devices in one or more directions and more particularly to devices of this character adapted for use with automotive or other internal combustion engines to prevent stalling when the throttles thereof are suddenly released.

One object of the present invention is to provide a reliable and highly improved antistall means for internal combustion engines.

Another object is to provide an antistall device which is adapted for ready installation on internal combustion engines now in use as well as on those in the process of manufacture.

A further object is to provide a dash pot of the diaphragm type in operative association with the carburetors of automotive engines to prevent stalling of the latter when their control throttles are suddenly released.

A still further object is to provide a dash pot of the stated character which is simple in construction, economic in manufacture and highly efficient in operation.

A still further object is to provide a variable chamber mechanism wherein the chamber is divided into two compartments by a diaphragm and wherein the said diaphragm and the supporting plates therefor provide valve means to permit fluid flow through the said diaphragm during movement of the latter in one direction.

Other and further objects will become apparent as the description of the invention progresses.

Of the drawings:

Fig. 1 is a fragmentary elevational view of an automobile engine carburetor having the antistall device incorporating the present invention operatively connected with throttle control means associated therewith.

Fig. 2 is a longitudinal sectional view of the 40 antistall device taken substantially along line 2—2 of Fig. 1, and

Fig. 3 is an exploded perspective view of several of the operating parts of the antistall device shown in Figs. 1 and 2.

Referring to the drawing and more particularly to Fig. 1 thereof, the numeral 10 indicates a portion of a downdraft carburetor which is adapted for operative connection to an automotive or other internal combustion engine (not shown).

2

A throttle valve (not shown) having an operating shaft 11 is provided in carburetor 10. Shaft 11 projects through a coupling 12 which connects the carburetor 10 to the manifold of the engine with which the said carburetor is employed. A valve operating lever 13 actuatable by a rod 14 is secured to the flattened end of shaft 11 as shown in Fig. 1. One end of rod 14 is pivotally connected to lever 13 as shown at 16 while the opposite end of said rod may be connected to an accelerator pedal or other suitable device for actuating lever 13 from any remote position, by means of links and levers or other intermediate connecting means (not shown).

15 The throttle for carburetor 10 has a suitable idling position at which it is partly open at all times for the purpose of admitting to the engine a sufficient charge of fuel to maintain the said engine in operation at low speed and generally at no load. Such idling position of the throttle for the carburetor 10 is determined by a screw 17 which is adjustably secured in a threaded opening formed in a part 18 of the lever 13. The opposite end of the screw 17 beyond the part 18 is adapted to engage any suitable stop projecting from the casing of the carburetor 10. A suitable spring not shown but generally associated with rod 14 is adapted to resiliently urge lever 13 into a position in which the end of the screw 17 will engage the stop referred to.

It will be apparent from the structure disclosed that the throttle valve will be opened when the lever 13 is rotated in a counterclockwise direction by pulling upon rod 14 and will be moved toward closed or to idling position when the lever 13 is rotated in an opposite direction by an opposite movement of the rod 14 and into a position in which the screw 17 engages the idling stop referred to.

35 The lever 13 is also provided with a laterally projecting arm 19 which is adapted to engage and operate in one direction the actuating rod or shaft 21 of an antistall device indicated generally by numeral 22. Antistall device 22 is provided with a casing 23 comprising two sections 24 and 26, which, as will appear more fully later herein, are secured together at their outer rims. Rod 21, it will be observed, extends through the bore 27 of an externally threaded sleeve 28. The 45 reduced inner end 29 of sleeve 28 extends through

an opening 38 provided in a cup-shaped depression 34 disposed centrally of casing section 26, the outer wall 32 of said depression in assembly, abutting the annular shoulder 33 on said sleeve 28. When the parts have been so assembled the wall 32 of depression 34 is welded or otherwise rigidly secured to the reduced end 29 of sleeve 28. Antistall device 22 is secured to a bracket 34 which in turn is secured in any suitable manner to the casing of carburetor 10. As shown in Figs. 1 and 2, bracket 34 has a relatively flat supporting portion 35 provided with an opening 36 for receiving sleeve 28. A spacing washer 37 is disposed between and engages supporting portion 35 and the inner end of a nut 38 making threaded engagement with sleeve 28. The outer wall 32 of depression 34 is rigidly secured to flat portion 35 of bracket 34 by welding or by any other suitable means. Thus when nut 38 is tightened washer 37 is brought into intimate contact with the supporting portion 35 of bracket 34. The antistall unit 22 is therefore effectively held in proper position on bracket 34.

A stud 39 having a head 40 is press fitted into the outer tubular end of rod 21. The stud 39, obviously, may be forced into the opening in shaft 21 to any desired extent. The length of rod 21 thus may be adjusted to the proper position with respect to throttle lever 13 of the carburetor 10. The antistall device 22 is in proper position on bracket 34 when the axis of the rod 21 makes substantially a right angle with a line passing through the axis of shaft 21 and the point of engagement of arm 19 and stud 39 when the throttle operating lever 13 is in engine idling position.

Casing section 24 comprises an outwardly depressed cup-shaped portion 41, offset annular end walls 42' and 42 and an inwardly and upwardly inclined annular wall 43 which terminates in a vertically disposed rim or flange 44. The casing section 26, in addition to the cup-shaped depressed portion 34 also comprises a substantially vertical annular end wall 45 and an upwardly and inwardly inclined annular wall 46 which terminates in a vertical outer rim or flange 47. A flexible diaphragm 48 is secured between the flanges 44 and 47 of casing sections 24 and 26 by crimping the outwardly projecting flange 47 around flange 44 as shown at 49 in Fig. 2.

The central portion of diaphragm 48 is reinforced on either side thereof by a pair of substantially circular valve plates 50 and 51. Plates 50 and 51 have oppositely disposed flanges 52 and 53, respectively, provided on the peripheral edges thereof, flange 52 being adapted to engage end wall 42 of casing section 24 to limit the movement of diaphragm 48 in one direction while flange 53 is adapted to engage end wall 45 of casing section 26 to limit the movement of said diaphragm in the opposite direction.

A coil spring 54 having one end disposed within and engaging the outer wall of depressed portion 41 of casing section 24 and the opposite end abutting the central portion of plate 50, tends to resiliently urge the diaphragm 48 to the right or what might be termed as the expanded position of the diaphragm. In such position of diaphragm 48 the flange 53 of plate 51 rests against the end wall 45 of casing section 26, as shown by broken lines in Fig. 2. The diaphragm 48 is moved toward and away from the expanded position referred to by the shaft 21 which is operatively connected to the said diaphragm and

the plates 50 and 51 by securing means which will be later described.

Diaphragm 48 divides casing 23 into two compartments or chambers 56 and 57 and certain valve means are provided which enable air to flow freely between said compartments when the said diaphragm moves to the right or to the expanded position and which causes restricted flow between said compartments when the diaphragm moves to the left or toward idling position. Diaphragm 48 and plates 50 and 51 each have provided centrally thereof a key shaped opening 58 having a substantially semicircular lower portion 59 for receiving the correspondingly shaped inner end 60 of rod 21 and an upper relatively short and narrower portion 61 communicating therewith. Disposed between the inner end 60 and shaft 21 proper the latter also has provided thereon an enlarged portion 62 having an annular axially extending flange 63 disposed near the periphery of the inner side thereof forming a recess 64. A metering plate 65 is disposed between flange 63 and plate 51 and also has a substantially semicircular opening 66 therein for receiving the inner end 60 of shaft 21 and a relatively long and narrow metering slot 67. Slot 67 is in axial alignment with the slots 61, and, as shown in Fig. 2 extends above the periphery of the enlarged portion 62 of rod 21 so as to communicate with compartment 57. A breather plate 68 having a substantially semicircular opening 69 therein for receiving the inner end 60 of rod 21 engages plate 50. The innermost end of rod 21 has a substantially cylindrical portion 70 provided thereon for receiving a holding washer 71. After the parts have been assembled on the inner end of rod 21 the cylindrical portion is peened over washer 71 thereby securely clamping the parts in position. Breather plate 68 has provided therein depressions 72 and 73 disposed at substantially right angles to each other and extending across opening 69 thereby forming passages between plates 68 and 50 which communicate with slots 61 and through which small amounts of air may flow to and from compartment 56. Diaphragm 48 and plate 50 have aligned openings 74 and 75, respectively, therein through which air may rapidly flow from compartment 57 to compartment 56 when diaphragm 48 moves to the right or expanded position. When diaphragm 48 moves to the left or toward engine idling position opening 75 is closed by plate 51 and consequently air from compartment 56 may flow to compartment 57 only through the depressions in breather plate 68 and slots 61 and 67. The recess 64 provided between enlarged portion 62 of shaft 21 and plate 51 communicates with the passages formed by slots 61 and 67. The passages defined by the slots 61 and 67 are so designed that the cross sectional area of slot 67 through which air from compartment 56 escapes into compartment 57 or through which air from compartment 57 flows to compartment 56 constitutes the most restricted portion of the passage and consequently any desired amount of air to be metered may be obtained by merely changing the size of slot 67.

Plate 50, it will be observed, is dished so that the annular portion thereof extending from and beyond opening 75 diverges from plate 51 forming a space 76 therebetween. By this construction of plate 50 diaphragm 48 is adapted to move relative to plates 50 and 51 from the position shown in Fig. 2 against plate 51 wherein open-

ing 14 is closed to a position against plate 50 wherein opening 74 is spaced from plate 51 and consequently air may flow freely between compartments 56 and 57 through openings 74 and 75.

From the foregoing description it is seen that when the throttle is opened or moved away from the idling position by pulling on rod 14 and thereby rotating lever 13 in a counterclockwise direction, spring 54 will cause rod 21 to follow arm 19 until the diaphragm reaches its expanded position.

Upon the initial movement of diaphragm 48 away from casing section 24 a reduction is pressure occurs in chamber 56 and an increase of pressure in chamber 57 causing diaphragm 48 to move away from plate 51 toward plate 53 thereby uncovering opening 74 and permitting air to flow freely from compartment 57 to compartment 56. Spring 54, therefore, encounters little resistance and as a result the movement of diaphragm 48 and shaft 21 is as rapid as that of lever 13 which the said shaft follows. When in fully expanded position the flange 53 on plate 51 is in engagement with the end wall 45 of casing section 26. The parts remain in this position until rod 14 actuates lever 13 in a clockwise direction at which time arm 19 acting on stud 39 at the end of lever moves the latter to the left against the pressure of spring 54. Upon initial movement of rod 21 in this manner the pressure in chamber 57 is slightly reduced while the pressure in chamber 56 increases, and, consequently, the diaphragm 48 is moved against plate 51 thereby closing the opening 74 in said diaphragm. All air flowing from compartment 56 to compartment 57 must now flow through the passages between breather plate 68 and plate 50 and slots 61 and 67. As a result the movement of diaphragm 48 to the left or to idling position is relatively slow and therefore movement of the throttle to idling position is gradual. Stalling of the engine by a sudden or rapid movement of the throttle to idling position from a more open position thereof is thus effectively prevented. When diaphragm 48 reaches idling position the flange 52 on plate 50 abuts end wall 42 of casing section 24.

From the foregoing description it is seen that a simplified and highly improved antistall device has been provided. Inasmuch as the device is comprised of but a few simple parts efficient operation thereof is assured over a long period of time.

It will be apparent that changes and modifications may be made in the device disclosed without departing from the invention. It is also apparent that the invention shown and described herein is adapted for wide and varied uses other than that as a dash pot. It is intended, therefore, that the invention should be limited only by the scope of the claims which follow.

What is claimed is:

1. A dash pot, comprising, a casing, a diaphragm dividing said casing into two compartments, a circular plate disposed at either side of said diaphragm, one of said plates being dished to provide a space between said plates over a portion of the area thereof, one of said plates and said diaphragm having aligned openings therein positioned opposite said portion, through which air may freely flow between said compartments when said diaphragm is moved in one direction and through which airflow is prevented when said diaphragm is moved in the other direction, means providing a restricted passage between

said compartments, and operating means for said diaphragm.

2. A dash pot comprising a casing, a diaphragm dividing said casing into two compartments, a plate disposed adjacent one side of said diaphragm, said plate and diaphragm having aligned openings therein, a second plate disposed adjacent the other side of said diaphragm and adapted to cover the said opening in said diaphragm when the latter moves in one direction, said diaphragm moving away from said second plate when actuated in the opposite direction, a dished portion on one of said plates providing a space between said plates permitting air to flow between said compartments through said openings when said diaphragm moves in said opposite direction, means providing a restricted passage between said compartments, and operating means for said diaphragm.

3. A dash pot, comprising, a casing, a diaphragm dividing said casing into two compartments, a plate disposed adjacent one side of said diaphragm, said plate and diaphragm having aligned openings therein through which air may flow between said compartments, a second plate disposed adjacent the other side of said diaphragm adapted to cover the said opening in said diaphragm when the latter is moved in one direction, said diaphragm moving away from said plate to uncover said opening when moved in the opposite direction, an annular dished portion on said first plate extending from the opening therein to the outer end thereof providing a space between said plates to permit air to flow between said compartments through said openings when said diaphragm moves in said opposite direction, and operating means for said diaphragm and plates.

4. A throttle dash pot for internal combustion engines, comprising, a casing, a diaphragm dividing said casing into two compartments, a valve plate disposed on each face of said diaphragm, one of said plates and said diaphragm having aligned openings therein through which air may freely flow between said compartments when said diaphragm moves in one direction, the other of said plates engaging the face of said diaphragm and being adapted to close the said opening in said diaphragm when the latter moves in the opposite direction, said diaphragm and valve plates having aligned slots therein, a breather plate disposed adjacent one of said valve plates forming therewith one or more passages communicating with said aligned slots, a metering plate disposed adjacent the other of said valve plates having a metering opening therein communicating with said aligned slots, an operating rod for said diaphragm, means on said rod for supporting said plates, and means for clamping together said plates and diaphragm on said rod.

5. A throttle dash pot, comprising, a casing, a diaphragm having an air opening therein and dividing said casing into two compartments, a valve plate disposed at either side of said diaphragm for controlling the flow of air between said compartments through the said opening in said diaphragm, a breather plate disposed adjacent one of said plates and forming therewith one or more air passages, an air metering plate disposed adjacent said other valve plate having a metering slot therein, said diaphragm and valve plates having aligned slots therein forming an air passage communicating with the passages in said breather plate and said metering slot, an operating rod for said diaphragm and plates

mounted for reciprocation in said casing, supporting means on said rod of substantially semi-circular cross sectional shape for said valve, breather and metering plates and said diaphragm, said valve, breather and metering plates and said diaphragm having openings therein corresponding to said supporting means for receiving the latter, and means for securing said valve, breather and metering plates and said diaphragm in position on said supporting means.

6. A throttle dash pot, comprising, a casing, a diaphragm mounted in said casing dividing the latter into two compartments, and valve means for controlling the rate of movement of said diaphragm, said last mentioned means comprising a valve plate disposed at either side of said diaphragm, one of said valve plates and said diaphragm having aligned openings therein through which air may freely pass between said compartments when said diaphragm moves in one direction, the other of said plates being adapted to close the said opening in said diaphragm when the latter moves in the opposite direction, means provided on one of said plates to permit a limited relative movement between said diaphragm and said valve plates to effect opening and closing of the opening in said diaphragm, an operating rod mounted in said casing, means on said rod for supporting said plates, means for clamping said plates to said diaphragm, and means providing a relatively small passage between said compartments through which small quantities of air may pass, thereby retarding the movement of said diaphragm in the said opposite direction.

7. A throttle dash pot, comprising, a sectional casing, a diaphragm secured between the sections of said casing dividing the latter into two compartments, an operating rod for said diaphragm extending through and mounted for reciprocation centrally of one of said casing sections, and valve means for controlling the rate of movement of said diaphragm, said means comprising a valve plate disposed at either side of said diaphragm, one of said valve plates and said diaphragm having aligned openings therein through which air may freely flow between said compartments when said diaphragm moves in one direction, the other of said plates being adapted to close the said opening in said diaphragm when the latter moves in the opposite direction, one of said valve plates being dished so as to provide a space between said valve plates to permit relative movement of the latter and said diaphragm to effect opening and closing of the said opening in said diaphragm, means on said rod for supporting said plates, means for clamping said plates to said diaphragm, and said valve plates and diaphragm having aligned slots therein adjacent said rod through which relatively small amounts of air may flow between said compartments, thereby retarding the movement of said diaphragm in said opposite direction.

8. A throttle dash pot, comprising, a sectional casing, a diaphragm secured between the sections of said casing dividing the latter into two compartments, an operating rod for said diaphragm extending through and mounted for reciprocation centrally of one of said casing sections, and valve means for controlling the rate of movement of said diaphragm, said means comprising a valve plate disposed at either side of said diaphragm, one of said valve plates and said diaphragm having aligned openings therein through which air may freely flow between said compartments when said diaphragm moves in

one direction, the other of said plates being adapted to close the said opening in said diaphragm when the latter moves in the opposite direction, one of said valve plates being dished so as to provide a space between said valve plates to permit relative movement of the latter and said diaphragm to effect opening and closing of the said opening in said diaphragm, said valve plates and diaphragm having aligned slots therein, air metering means disposed adjacent one of said valve plates for controlling the flow through said slots of small amounts of air between said compartments thereby retarding the movement of said diaphragm in said opposite direction, supporting means on said rod for said plates and metering means, and means for clamping together said valve plates, diaphragm and metering means on said rod so as to move as a unit therewith.

20 9. A throttle dash pot, comprising, a sectional casing, a diaphragm secured between the sections of said casing dividing the latter into two compartments, an operating rod for said diaphragm extending through and mounted for reciprocation centrally of one of said casing sections, and valve means for controlling the rate of movement of said diaphragm, said means comprising a valve plate disposed at either side of said diaphragm, one of said valve plates and said diaphragm having aligned openings therein through which air may freely flow between said compartments when said diaphragm moves in one direction, the other of said plates being adapted to close the said opening in said diaphragm when the latter moves in the opposite directions, one of said valve plates being dished so as to provide a space between said valve plates to permit relative movement of the latter and said diaphragm to effect opening and closing of the said opening in said diaphragm, said valve plates and diaphragm having aligned air slots therein adjacent said rod, a breather plate disposed adjacent one of said valve plates, and forming therewith one or more passages for air communicating with said air slots, a metering plate disposed adjacent the other of said valve plates having an air metering slot therein communicating with said first mentioned slots through which relatively small amounts of air may flow between said compartments, thereby retarding the movement of said diaphragm in the said opposite direction, supporting means on said rod for said valve, breather and metering plates, and means for clamping together said breather valve and metering plates and said diaphragm on said rod so as to move together as a unit with the latter.

10 10. A throttle dash pot, comprising, a sectional casing, a diaphragm secured between the sections of said casing dividing the latter into two compartments, an operating rod for said diaphragm extending through and mounted for reciprocation centrally of one of said casing sections, and valve means for controlling the rate of movement of said diaphragm, said means comprising a valve plate disposed at either side of said diaphragm, one of said valve plates and said diaphragm having aligned openings therein through which air may freely flow between said compartments when said diaphragm moves in one direction, the other of said plates being adapted to close the said opening in said diaphragm when the latter moves in the opposite direction, one of said valve plates being dished so as to provide a space between said valve plates

to permit relative movement of the latter and said diaphragm to effect opening and closing of the said opening in said diaphragm, said valve plates and diaphragm having aligned slots therein, air metering means disposed adjacent one of said valve plates for controlling the flow through said slots of small amounts of air between said compartments thereby retarding the movement of said diaphragm in said opposite direction, supporting means on said rod for said plates and metering means, means for clamping together said valve plates, diaphragm and metering means on said rod so as to move as a unit therewith, a spring disposed between one of said casing sections and one of said valve plates for actuating said diaphragm in said one direction, and a throttle valve actuating lever engaging said rod to operate said diaphragm in the said opposite direction.

11. A throttle dash pot, comprising, a sectional casing, a diaphragm secured between the sections of said casing dividing the latter into two compartments, an operating rod for said diaphragm extending through and mounted for reciprocation centrally of one of said casing sections, and valve means for controlling the rate of movement of said diaphragm, said means comprising a valve plate disposed at either side of said diaphragm, one of said valve plates and said diaphragm having aligned openings therein through which air may freely flow between said compartments when said diaphragm moves in one direction, the other of said plates being adapted to close the said opening in said diaphragm when the latter moves in the opposite direction, one of said valve plates being dished so as to provide a space between said valve plates to permit relative movement of the latter and said diaphragm to effect opening and closing of the said opening in said diaphragm, said valve plates and diaphragm having aligned slots therein, air metering means disposed adjacent one of said valve plates for controlling the flow of small amounts of air through said slots thereby retarding the movement of said diaphragm in said opposite direction, supporting means on said rod for said plates and metering means, means for clamping together said valve plates, diaphragm and metering means on said rod so as to move as a unit therewith, a spring disposed between one of said casing sections and one of said valve plates for actuating said diaphragm in said one direction, a throttle valve actuating lever engaging said rod to operate said diaphragm in the said opposite direction, and stop means on said valve plates engaging said casing sections to limit the movement of said diaphragm in either direction.

12. A throttle dash pot, comprising, a sectional casing, a diaphragm secured between the sections of said casing dividing the latter into two compartments, an operating rod for said diaphragm extending through and mounted for reciprocation centrally of one of said casing sections, and valve means for controlling the rate of movement of said diaphragm, said means comprising a valve plate disposed at either side of said diaphragm, one of said valve plates and said diaphragm having aligned openings therein through which air may freely flow between said compartments when said diaphragm moves in one direction, the other of said plates being adapted to close the said opening in said diaphragm when the latter moves in the opposite direction, one of said valve plates being dished

so as to provide a space between said valve plates to permit relative movement of the latter and said diaphragm to effect opening and closing of the said opening in said diaphragm, said valve plates and diaphragm having aligned air slots therein adjacent said rod, a breather plate disposed adjacent one of said valve plates, and forming therewith one or more passages for air communicating with said air slots, a metering plate disposed adjacent the other of said valve plates having an air metering slot therein communicating with said first mentioned slots through which relatively small amounts of air may flow between said compartments, thereby retarding the movement of said diaphragm in the said opposite direction, supporting means on said rod for said valve, breather and metering plates, means for clamping together said breather valve and metering plates and said diaphragm on said rod so as to move together as a unit with the latter, a spring disposed between one of said casing sections and one of said valve plates for actuating said diaphragm in said one direction, a lever engaging said rod to operate said diaphragm in the said opposite direction, and stop means on said valve plates engaging said casing sections to limit the movement of said diaphragm in either direction.

13. In a diaphragm controlled pressure differential chamber, a casing having an interior cavity, a diaphragm unit dividing said cavity into two compartments, said diaphragm unit including a flexible diaphragm and a pair of plates disposed on opposite sides of said flexible diaphragm, said diaphragm unit having a valve portion, one of said plates being dished to provide a space between said plates for free movement of said flexible diaphragm at said valve portion of said diaphragm unit, one of said plates and said flexible diaphragm having aligned openings therein positioned in said valve portions of said diaphragm unit through which air may freely flow between said compartments when said diaphragm unit is moved in one direction and said flexible diaphragm contacts said one of said plates having an opening, and flow through said openings is prevented when the diaphragm unit is moved in the other direction and said flexible diaphragm contacts the other plate with respect to said one of said plates having an opening, and operating means for said diaphragm unit.

14. A variable chamber mechanism having a chamber divided into two portions by a diaphragm, said diaphragm having a one-way valve mechanism, said valve mechanism comprising an opening in said diaphragm, a pair of plates disposed on opposite sides of said diaphragm, one of said plates having an opening aligned with said diaphragm opening, the other of said plates adapted to close said diaphragm opening when the diaphragm is moved in one direction, said diaphragm being adapted to move away from said other plate when moved in the opposite direction, one of said plates having a dished portion providing a space between it and the other plate permitting flow of fluid between said chamber portions through said diaphragm and plate openings when the diaphragm is moved in said opposite direction, and operating means for said diaphragm.

15. A diaphragm controlled pressure differential chamber comprising, a casing, a diaphragm attached to said casing and separating said casing into two chambers, an aperture formed in said diaphragm, a rigid plate mounted adjacent

to said diaphragm having a portion adapted to close said aperture, said plate being mounted so that the plane of the closing portion of said plate is substantially parallel to the plane of the diaphragm in the area of said aperture and contacting said diaphragm completely around said aperture during movement of said diaphragm in one direction, means attached to the diaphragm for moving the same to a position out of parallelism with the plane of said closing portion of said plate in the area of said aperture, and out of complete contact with said plate around said aperture during movement of said diaphragm in the opposite direction, whereby the plate closing portion is ineffective to close 15 said diaphragm aperture.
